UNITED STATES PATENT OFFICE.

MAX ROCKSTROH, OF KLEIN-SEDLITZ, NEAR PIRNA, GERMANY.

PLATEN-PRESS.

1,401,818.

Specification of Letters Patent. Patented Dec. 27, 1921.

Application filed October 12, 1920. Serial No. 416,584.

To all whom it may concern:

Be it known that I, MAX ROCKSTROH, manufacturer, a citizen of the German Republic, residing at Klein-Sedlitz, near Pirna,

5 Saxony, Germany, have invented certain new and useful Improvements in Platen-Presses, (for which I have filed application in Germany on July 25, 1916,) of which the following is a specification.

10 My invention relates to platen presses provided with automatic devices for feeding and delivering the sheets of paper, and a primary object is to provide an improved platen press of this type comprising various

15 devices which are known in themselves, but are combined and arranged in an improved manner such that various new and considerably improved results are obtained. A novel feature of the invention is the com-

20 bination of a rectilinearly reciprocating platen, several gripping devices which are rotatable about the same and are actuated in such a manner that the rotation of a drum carrying the grippers begins exactly at the

25 change of stroke of the platen independently of the position of the latter due to the regulator, and a device for opening and closing the grippers, by means of which the sheet is always caught in the same posi-

30 tion of the platen relatively to the form independently of the regulator.

Platen presses are well known, in which the gripping devices are led on endless belts over rollers around the platen and participate in the movement of the latter. In these devices the sheet is fed directly to the grippers, the fixed parts of the grippers being provided with marks, against which the sheet is pressed by the conveying means

40 on the laying-on board and is seized by the grippers when the stroke of the platen changes. The change of stroke of the platen in the open position does not, however, always take place in the same position rel-

45 atively to the laying-on board in platen presses having a movable platen. This is due to the pressure being adjusted by the eccentricities on the shaft of the platen to an amount which varies with each kind of

50 work. The greater the eccentricity of the eccentricities the nearer the grippers approach to the laying-on board when the stroke changes. The grippers are nearest to it when the pressure is entirely absent. The

55 grippers are opened and closed by a device which always exercises a constant ef-

fect with regard to the main cranks whereby the grippers are closed, however in various positions of the platen. In some cases the sheet is gripped earlier and in others 60 later, according to the position of the pressure regulator. As the sheet is pressed by the conveying means against the marks in the gripping devices, it also has to participate in the differences in the end position of 65

the grippers. Consequently, in one position of the regulator it will exactly reach the marks, while in another position the marks have to press the sheet back. As this movement takes place in a direction con-

70 trary to the direction of motion of the conveying means, if the paper is thin the sheets will consequently be crumpled. Further, such gripping devices provided with marks have to be made very accurately and exactly 75

alike, and must be provided with an arresting device in the removing and printing position, in order to obtain exact register. Owing to the gripping devices being guided over rollers, when the sheet is be-

80 ing conveyed to the place, where it is printed and laid off it has to be sharply bent, which, however, is a disadvantage when the paper is thick.

Platen presses having revolving gripping 85 devices are also known. These comprise a fixed platen, however, so that the laying-on board must be arranged far below the platen which renders the adjustment of the marks and the like very difficult and the 90

feed of the sheets not easily observed. Also, these printing presses have no parallel end movement of the platen for effecting the printing. Consequently, no work for which such parallel movement is a preliminary 95 condition can be done on these presses.

Further, platen presses are known in which grippers arranged at the lower edge of the platen withdraw the sheet, when swinging into position for the impression, 100 from a laying-on board located above the platen, the arrangement being such that the grippers always close at the same place. This kind of feed of the sheets, however, has the great defect that the sheet is brought 105 from above onto the platen, which readily leads to the collapse of the sheet when the paper is thin.

A primary object of my invention is to provide an improved platen press having 110 an automatic feeding and delivery device comprising revolving grippers to which the de-

fects above referred to are not attached. To this end, in my improved press the gripping devices which revolve about the platen and feed the sheet from below are arranged 5 on a reciprocating platen and are influenced in such a manner by a closing device that the grippers are always closed in the same open position of the platen independently of the regulator, or, alternatively, their operation 10 can be interrupted when desired by the operator.

To these ends the invention consists in the construction, arrangement and combination of parts described hereinafter and pointed 15 out in the claims.

One illustrative embodiment of the invention is diagrammatically represented by way of example in the accompanying drawings, wherein:

20 Figure 1 is a side elevation, partly in section, showing part of my improved platen press comprising a rectil nearly reciprocated feeding and delivering device, the grippers being shown in open position.

25 Fig. 2 is a view similar to Fig. 1, the grippers being shown as closed and on the way to the printing position.

30 Fig. 3 is a view similar to Figs. 1 and 2, the grippers being shown in the printing position, and

Fig. 4 is a front end elevation of the press, the parts being in the same position as shown in Fig. 3;

35 Fig. 5 is a side elevation showing the feed mechanism for the grippers when the platen is in the printing position, and

40 Fig. 6 is a view similar to Fig. 5, the parts being shown in the position assumed shortly before the platen is in its open position.

45 Referring to the drawings, the bed 1 has eyes 2 and 3 in which are mounted rectilinear guides, in the embodiment round rods 4, which are disposed at right angles to the bed, and on which the platen 5 is guided. This platen has side walls 6 and 7, which have lugs 8 and 9 guided by the rods 4, and it has bearings 10, on which rings 11 are rotatable. These rings are connected to 50 together by members 12 which together constitute a drum. The members 12 each has a gripping device associated therewith and they are turned or switched in such a manner that one gripping device is always ready for taking a sheet from the laying-on board 20. The connecting members 12 have parts formed as lower jaws 13, and have bosses 14 for carrying the gripper rods 15 and the upper jaws 19. These rods carry 55 levers 16 having antifriction rollers 17 which are used for actuating the jaws 19 and thereby opening the grippers. The laying-on board 20 is arranged at the end of the path of the platen. The sheet is laid 60 by hand or mechanically on the laying-on

board 20 or on conveying means 18 provided at the latter, and is pushed against the marks 21 provided at the lower end thereof, where it is adjusted. For withdrawing the sheet from the board or other 70 means the platen is driven to the right along the rods 4 by means of cranks 22 which are connected with the shaft 24 of the platen by rods 23. Before the platen arrives at its outer end position the roller 17 runs onto 75 the tripping member 27 which is fulcrumed at 26 and is held in its normal position by a counterweight 28, whereby the member 27 is rocked and the grippers are opened. As the platen moves farther outward the 80 roller 17 leaves the member 27, the latter rocks back into its normal position and the roller rolls on the inclined way 25. On the return stroke of the cranks 22 the roller 17 rolls back down the inclined way 25, where- 85 by the grippers 19 always close and seize the sheet at the same place. At the same time the marks 21 are lowered and the rings 11 are turned in the manner described hereinafter, and the sheet is conveyed onto 90 the platen.

In the embodiment shown, the drum 11, 12 is turned by means of a lever 31 (Figs. 5 and 6) which is mounted to swing about the shaft 24 of the platen and is driven by 95 means of toothed segments 34, 33 and an arm 33', on the latter carrying an antifriction roller 41 running in a curved way 41' formed in a bracket 32 carried by the bed 1. The lever 31 carries a bolt or latch 35 whose 100 wedge-shaped end 36 can take into wedge-shaped recesses 38 in the ring 11. The bolt or latch 35 carries a laterally extending pin 40, and a spring 37 arranged between the pin 40 and an abutment formed on or carried by the lever 31 tends to draw the latch 35 inwardly; that is to say, toward the shaft 34, so as to cause the wedge-shaped end 36 of the bolt or latch 35 to enter or snap into the notches 38 of the ring 11 when said 110 wedge-shaped end arrives opposite said notches. The wedge-shape of the end of the latch which drives the ring is particularly suitable because, although the angle of oscillation of the lever 31 will vary according 115 to the printing position at the time, the ring 11 can be evenly driven by the lever 31. The shape and arrangement of the curved way 41' cause any difference in the magnitude of the swing of the lever to be 120 evident only in the open position of the platen, that is to say only at the commencement of the feed movement of the lever, the result being that when the amplitude of swing of the lever 31 is small, the wedge 36 enters 125 only a short distance into the recess 38, while when the swing of the lever is larger the wedge enters a greater distance into said recess. In order that the ring shall not be turned varying distances, I arrange that, in 130

the course of the turning of the ring, the wedge is positively drawn entirely into the recess 38, so that the position of the lever 31 relatively to the ring 11 is always the 5 same toward the end of the turning movement of the ring.

To this end I provide a spring actuated hook 39 which is mounted to swing on a pivot arranged eccentrically to the shaft 24 of the platen as well as to the center of oscillation of the lever 31. When the ring begins to turn, after the latch 35 has snapped into a recess 38 the hook 39 takes over the pin 40 on the latch and, owing to its eccentric position, pulls the latch home into the recess. Shortly before the end of the return movement of the lever the hook abuts against a fixedly mounted stop 44 which arrests it and disengages it from the pin 40 so that the latch 35 may be disengaged from the recess 38 in the ring. This is brought about by means of a slide 45 which is mounted to reciprocate on the platen which is engaged and actuated by fixed stops 46 and 47 carried by the platen. In the position shown in Fig. 5 the slide 45 has been moved over into its outer position and the latch has been removed from the recess. In the position shown in Fig. 6 the slide 45 has 30 not yet reached its inner end position. An important function of the slide 45 is that it firmly locks the ring while it is stationary and thereby insures correct registration in the printing. The grippers are opened and 35 the sheet is delivered to the table 49 when the roller 17 coacts with the fixed stop 48. When this occurs the sheets fall out of the opened grippers into the table.

Owing to the centrifugal motion of the 40 grippers the paper or board to be printed is drawn around the platen in a curve corresponding in size to the circle, so that bending the sheet about an arc of short radius is avoided and thick paper, or even board, can 45 be fed and delivered.

By holding the rocking member 27 in the position shown in Fig. 1, the grippers can be put out of action, because the roller 17 will then roll back over the member 27 and 50 the grippers will remain open.

Instead of the above described device for closing the grippers any other may be used if it closes them exactly at the same place independently of the regulator.

55 Further, it is to be understood that I do not limit myself to the specific details of construction illustrated in the drawings and described in the specifications, as various changes, within the scope of the appended 60 claims, may be made without departing from the spirit of my invention.

I claim:

1. In a platen press, the combination with a platen and means for rectilinearly reciprocating the same, of a plurality of

gripping devices mounted about the platen, means for rectilinearly reciprocating the platen, means for revolving the gripping devices about the platen actuated by the movement of the platen, and means for 70 closing the gripping devices for seizing a sheet at the same open position of the platen, substantially as described.

2. In a platen press, the combination with a platen, means for rectilinearly actuating 75 said platen, a drum rotatable about said platen comprising spaced rings connected by transverse rods, grippers mounted upon said drum and cooperating means on said platen and drum for rotating said drum through 80 the motion of said platen.

3. In a platen press, the combination with a platen, a shaft carried thereby, and means connected with the shaft for rectilinearly reciprocating the platen into its open and 85 closed positions, of rings mounted to rotate about the platen, rods connecting the rings together, said rings and rods constituting a drum, grippers mounted on said drum, a lever mounted to swing about said shaft and 90 adapted to engage with said drum, positively guided driving means mounted on the platen and geared with said lever for rotating the drum, the commencement of the rotation of the drum coinciding exactly with the change 95 of stroke of the platen independently of the position of the platen, and means for closing the grippers in a predetermined position of the platen, substantially as described.

4. In a platen press, the combination with 100 a bed, a platen mounted thereon, a shaft carried by the platen, and means for rectilinearly reciprocating the platen into its open and closed position, of a drum mounted to rotate about the platen, grippers mounted 105 on the drum, a lever mounted to swing about said shaft and adapted to engage with and be disconnected from the drum, a curved guide on the bed, a toothed driving member pivoted on the platen, meshing with the 110 lever and positively guided by said guide, the shape of said guide being such that the commencement of rotation of the drum coincides exactly with the change of stroke of the platen independently of the position of 115 the platen, and means for closing the grippers during rotation of the same, substantially as described.

5. In a platen press, the combination with 120 a bed having an inclined way, a platen mounted to slide on the bed and means for rectilinearly reciprocating the platen, of rings mounted to rotate about the platen, a plurality of grippers mounted on the rings, each gripper comprising a fixed jaw and a 125 movable jaw having a driving arm, and a tripping member mounted to rock on the bed and adapted to coact with the driving arm of a gripper moving rectilinearly into end operative position, and thereby open the grip- 130

per, the driving arm normally sliding down said inclined way and closing the gripper when moving in the other direction adjacent thereto, substantially as described.

6. In a platen press the combination of a bed having an inclined way, a platen mounted to slide rectilinearly on the bed, a laying-on member located adjacent to said inclined way, rings mounted to rotate about the platen, a plurality of grippers mounted on the rings, means for reciprocating the platen and driving a gripper to and from the laying-on member, each gripper comprising a fixed jaw and a movable jaw having a driving arm, a tripping two-armed member, having a weight on one arm mounted to rock on the bed and adapted to coact with the driving arm of a gripper moving toward the laying-on member and thereby open the gripper, the driving-arm moving into the inclined way on leaving the tripping member and normally sliding down the same and thereby closing the gripper at the laying-on member, the tripping member being adapted to prevent the gripper closing when said weight is held elevated out of its normal position, and means for turning the rings, substantially as described.

7. In a platen press, the combination with a platen, a shaft carried thereby, and means connected with the shaft for rectilinearly reciprocating the platen into its open and closed position, of a ring having wedge-shaped recesses mounted to rotate about the platen, grippers mounted on the ring, a lever mounted to swing about said shaft, a

spring-pressed latch having a wedge-shaped end carried by the lever and adapted to take into said recesses, means mounted eccentrically on the shaft for positively drawing the latch into said recess, driving means mounted on the platen and geared with said lever for rotating the ring, and means for closing the grippers in a predetermined position of the platen, substantially as described. 45

8. In a platen press, the combination of a bed having two stops mounted thereon, a platen mounted to reciprocate rectilinearly on the bed, a shaft carried by the platen, means connected with the shaft for driving the platen into its open and closed positions, a ring having recesses mounted to rotate about the platen, grippers mounted on the ring, a lever mounted to swing about said shaft, a spring-pressed latch carried by the lever for taking into the recesses and thereby connecting the lever with the ring, driving means mounted on the platen and geared with said lever for rotating the ring, a slide mounted on the bed and adapted to coact with said stops and to take into and be removed from said recesses and thereby intermittently lock the ring, and means for closing the grippers in a predetermined position of the platen, substantially as described. 55 65

In testimony whereof I have hereunto set my hand in presence of two subscribing witnesses.

MAX ROCKSTROH.

Witnesses:
